STANDING EQUIPMENT UNITING A NUMBER OF
WORK SPACES FOR HAIRDRESSERSTheodor Kohl, Schwarze Barenstr. 6,
Regensburg, GermanyFiled Jan. 8, 1963, Ser. No. 250,067
9 Claims. (Cl. 312—227)

The invention has reference to standing equipment uniting a number of work spaces for hairdressers and standing free in the room, and particularly one wherein a mirror and a wash basin are a part of every work space and one having the mirrors forming the walls of a hollow, upright prism arranged above a work surface.

In the case of existing equipment of this kind the mirrors form a hexagonal prism so that six work spaces are present. The work surfaces for the spaces are relatively large and the work surface of every second space holds a wash basin with mixing means for cold and warm water as shown, for example, in French Patent 942,942. Because of the arrangement of the basin in the work surface, a large amount of space is needed and the work surfaces consequently project far into the room. However, in spite of this, there still remains practically no available work space for depositing working materials and equipment because the basin takes up practically the entire work space. Such standing equipment, if without the wash basin, are characterized by a small need for space, with equipment with a three-sided mirror prism representing an optimum. However, this advantage is completely lost by the arrangement of the wash basins in the work surface.

The invention aims at constructing standing equipment of the former kind in such a manner that the advantages of the small need for space is maintained in spite of the presence of a wash basin. To solve this problem, the invention provides that at least one of the mirrors is constructed as a window making possible entry into the interior of the prism; that within the prism there is at least one hair wash basin movable toward the outside with its outlet extending into the interior of the prism, and that finally in the foot of the standing equipment there is a collection pipe conducting away the water flowing from the basin. In this way there is not only no need for expanding the space for such equipment, but the work surface is also not reduced. In addition, the customers cannot see each other during the washing operation when the equipment is constructed as a three-sided mirror prism with swivel mirrors at each corner.

It is especially advantageous with regard to the use of the mirror window if according to the present invention every mirror window is constructed as a sliding window movable upwards in vertical tracks.

Furthermore, the inward and outward movement of the basins can be facilitated by supporting the basins swivelly around a horizontal axis attached behind each respective mirror. Thus, it is possible to arrange each basin upright behind the mirror on the swivel axis. This means that the hollow space of the mirror prism is sufficient for the storing of the basins without any necessity for enlarging the prism.

It is also advantageous for the utilization of available space if in the interior of the equipment below the outlet of the basin there is a collection basin connected with the outlet pipe. Thus, one single collection basin suffices for all hair wash basins. Also it can be cleaned easily.

The equipment can be constructed especially easily if according to the present invention the collection basin forms a unit with the work surface found underneath the mirrors. Furthermore, in the interior of the prism beside each wash basin a shower hose can be attached

2

wherein each hose is advantageously provided with a closing valve.

Depending upon the form of the work space, it is sometimes advantageous if according to the present invention the outlet of the wash basin is located swivelly on the horizontal axis and the basin is telescope-like attached to the outlet.

To produce a high rigidity of the standing equipment, it is advisable to connect the upper ends of the vertical tracks for the sliding windows by an upper part which 10 simultaneously serves as a bracket for at least one dryer movable on holders in the known fashion.

Additional characteristics of the invention are shown in the description below and in the drawing in which a construction example is shown.

FIGURE 1 shows a front view of the equipment.

FIGURE 2 shows the equipment from above.

FIGURE 3 shows an additional front view with two mirrors in a lifted position and the work surface shown in a cut.

15 The equipment consists of a frame formed by three vertical pipes 1 which at their upper and lower ends are rigidly connected by bars 2 and 3 on all sides. The three pipes 1 serve as supports for work surface 4 which also is arranged around the equipment at working height.

20 Covering walls 5 are arranged below work surface 4 and between the pipes. Above work surface 4 the walls of the three-sided prism are formed by mirrors 6 which are arranged in tracks of pipes 1 in such a manner that they can be slid upwards.

25 To hold the mirrors when in raised position bolts (not shown) of a usual kind are used. Above the mirrors there are again covering walls 8 between pipes 1 which, however, are not flush with mirrors 6 below them but are somewhat recessed so that mirrors 6 can be slid upwards in front of walls 8. Pipes 1

30 also carry turning mirrors 9 preferably radially pointing toward the outside, which both produce together with mirrors 6 a triple set of mirrors and separate each work space from each other in such a manner that the customers cannot see each other.

35 In the interior of the mirror prism formed by mirrors 6, three hair wash basins 10a, 10b and 10c are arranged each on a horizontal axis 11 whereby each can be swivelled toward the outside when mirror 6 is pushed up. In FIGURE 3 the basin 10a is shown in a normal upright position, while the basin 10c is shown in the lowered cut-side position in solid lines and is shown in raised position by broken lines. Basin 10 is with the help of bar 12 spaced from swivel axis 11 so that the basin when swung upright assumes a position in which it does not project

40 beyond the inner space of the three-sided prism, although swivel axis 11 lies relatively close behind mirror 6 so that when lowered the basin can be swivelled out to a maximum extent. At the lower end of each mirror, if desired, a snap lock (not shown) may be provided which holds the respective wash basin in the high position even when the window is pushed up. In this manner an involuntary swivel movement of the basin during the sliding motion of the window will be avoided.

45 Each basin 10 has at the swivel end an outlet 13 which when the basin is swivelled out is located above collection basin 14 in the interior of the prism. Collection basin 14 forms a unit with work surfaces 4 underneath mirror 10, with the work surfaces being extended into the hollow space of the three-sided prism and forming a trough in the center. Also there are indentations at the upper edges of collection basin 14 into which outlet 13 of each wash basin 10 can enter when the basins are lifted (FIGURE 3).

50 Underneath collection basin 14 is collection pipe 15, into which enters an extension branching off from exit 14'. It is possible to equip exit 14' with a sieve and the extension 16 with an odor stopper.

As seen in FIGURE 2 a shower hose 17 may be provided beside each basin. This hose is preferably extendable and can be equipped with a closing valve.

It is also possible to construct hair wash basin 10 in such a manner that the outlet for the basin has telescope characteristics. The outlet in this case is placed behind the mirror with the help of the swivel axis 11 and the wash basin after being swivelled out can be pushed in the direction of the customer.

For efficiency's sake, the upper bar 2 serves simultaneously as a bracket for one or more dryers (not shown) which with the help of known means can be moved in every desired direction. Lower bar 3, on the other hand, can also be used as a foot support and may be provided with a rubber surfacing 18.

Access to the wash basins in the interior of the prism can also be achieved if each mirror is constructed in the fashion of a window wing or of two such wings around one or two vertical axes, respectively, so that a swivelling toward the outside is possible. It is also possible to attach each mirror to pipes 1 in such a fashion that it can be removed.

Furthermore it is not absolutely necessary, to construct the several hair wash basins swivelly by means of horizontal axis 11. Each basin could also be equipped with a ring holder, with the help of which the basin could be placed upon a vertical bolt behind the mirror in order to secure the basin in a vertical position. The same or a second ring holder can be used to secure the basin in a horizontal position with the help of additional horizontal bolts.

The shape of the prism formed by mirrors 6 can in the sense of the invention be chosen as desired. Thus, the wash basins can also be stored in the interior of a four, five or multiformed prism, with one mirror window being found at each work space in the manner described above.

If the mirror is constructed as a window wing, it may be equipped with a holding device for its basin. It is also possible to attach the mirrors in such a manner that they can be pushed downward in vertical tracks.

Although a particular preferred embodiment of the invention has been disclosed above for illustrative purposes, it will be understood that variations or modifications which lie within the scope of the appended claims, are fully contemplated.

What is claimed is:

1. A free standing unit for providing a plurality of work spaces for hair dressers, comprising:

an upstanding base having a substantially horizontal work surface mounted thereon;

a plurality of mirrors on the base and defining the sides of a polygon, said polygon being above said work surface, and means mounting said mirrors for movement to expose the interior of the polygon;

collection means mounted inside of said polygon;

a plurality of wash basins each associated with one of said mirrors and positioned in the interior of the polygon behind its associated mirror, said wash basins being mounted for movement independently of the mirrors and being movable to a position outside of the polygon and above the work surface when the

interior of the polygon is exposed, each basin having an outlet for directing liquid into said collection means when said wash basin is in said position.

2. A free standing unit according to claim 1, in which the base includes a plurality of guides extending upwardly from the work surface, the mirrors being mounted on the guides for vertical sliding movement.

3. A free standing unit according to claim 1, in which each wash basin is supported by pivot means for pivotal movement about a horizontal pivot axis located inside of the polygon and adjacent its associated mirror.

4. A free standing unit according to claim 1, in which the collection means is a basin mounted on the work surface in the central region of the polygon.

5. A free standing unit according to claim 1, in which the outlet telescopes the remainder of the wash basin and the outlet is mounted for pivotal movement about a horizontal axis.

6. A free standing unit according to claim 2, in which an upper part is secured to and extends between the upper ends of the guides, said upper part serving as a support for at least one dryer.

7. A free standing unit for providing a plurality of work spaces for hair dressers, comprising:

a work surface;

a plurality of mirrors extending upwardly from the work surface, said mirrors being arranged to form a polygon;

vertical guides extending upwardly from the work surface and means mounting said mirrors for vertical movement along said guides so that said mirrors can be moved to expose the interior of said polygon;

a plurality of wash basins mounted within said polygon for pivotal movement about horizontal axes lying inside the polygon whereby said wash basins are covered when said mirrors are in their lower position and said basins are exposed when the mirrors are raised so that they can be pivoted to extend out of the polygon over the work surface.

8. A free standing unit according to claim 7, in which the mirrors form a three-sided polygon, each side being rectangular.

9. A free standing unit according to claim 7, in which each wash basin has an outlet which extends into the interior of the polygon when the wash basin extends out of the polygon, and including a collection basin mounted on the work surface in the interior of the polygon for receiving liquids flowing through the outlet; and a discharge conduit extending downwardly from the collection basin.
